W. P. KING

FASTENER FOR DOORS OF LAUNDRY WASHERS

Filed Feb. 25, 1926

Patented Aug. 10, 1926.

1,595,664

UNITED STATES PATENT OFFICE.

WILLIAM P. KING, OF SYRACUSE, NEW YORK.

FASTENER FOR DOORS OF LAUNDRY WASHERS.

Application filed February 25, 1926. Serial No. 90,606.

This invention relates to fasteners for doors of laundry washers and the like, and has for its object to provide novel, simple and automatic means for gripping and holding the doors in the open position, to enable the operator to fill and empty the tubs; the said fasteners being designed particularly for preventing accidental closing of the doors and injuring the operator's hands. A further object is to provide a pedestal, which may be mounted between the spaced doors of the well-known cylindrical washers, and to pivotally mount upon said pedestal similar latch-bars, which are arranged to partially overhang the adjacent end margins of the doors; the said latch-bars having teeth for engaging parts of the doors, and being arranged to yield away from the doors, when the latter are raised, and then to spring back toward the doors and grip said margins, for holding the doors ajar. And a further object is to provide means for adjusting the latch-bars, when the spaces between the doors vary, the said latches being released by the operator swinging their free ends away from the doors, for disengaging the said teeth.

I attain these objects by the means set forth in the detailed description which follows, and as illustrated by the accompanying drawings, in which—

Figure 1 is a top plan view of a cylindrical laundry washer having similar aligning doors, between which my improved fastener is applied. Fig. 2 is a broken end elevation of the same in which the full lines show one of the doors of the rotatable cylinder closed, the dotted lines showing the door held in the open position by one of the latches. Fig. 3 is a broken top plan view of a washer having a single door, to which a modified fastener equipped with a single latch is applied. And Fig. 4 is a broken end view and partial vertical section of the same, the section being taken on line 4—4 of Fig. 3.

In the drawing, 2 represents the outer cylindrical body of a laundry washer, the driving and certain other parts being omitted. 3—3' represent the inner rotatable cylinders, which contain the wash (not shown), and which are provided with the usual doors 4—4', for closing openings 4^a, that afford access to the interior of the enclosed cylinders. These doors are hinged at 4^b, and are swingable through the corresponding openings 3^a of the stationary cylin-

der 2. The openings 3^a are usually arranged to be closed, by means of slide-covers or doors 3^c, during the washing operations.

The doors 4—4' are shown fitted with open metal facings 4^c, which normally project at the end and bottom edges of doors, for forming flanges or valances 4^d, that overlap the margins of the openings 4^a when the doors are closed. These flanges 4^d frictionally engage the adjustable latch-members of the fasteners.

The fastener shown in Figs. 1 and 2, comprises a pedestal 5, which is provided with a foot-flange 5', that is perforated to receive screws 5^a, by which the said flange may be rigidly secured to the main cylinder 2, preferably between the openings 3^a. Upon the pedestal 5 is rigidly mounted an elongated plate 6, which is disposed at right angles to the foot-flange 5', the said plate being perforated at intervals, as at 6', for rendering parts of the fastener adjustable. 7—7' represent the swingable latching members which comprise similar elongated irregular-shaped metal arms, the corresponding ends of said arms being perforated to receive screws 7^a, which engage the holes 6', for pivotally mounting the arms upon the plate 6. The perforated ends of the arms 7—7' are thickened for forming shoulders 7^b which loosely over-lap the rear edge of the plate 6, and limit the swinging movements of said arms in opposite directions, towards and away from the doors 4—4'. Intermediate their ends the arms 7—7' are formed with similar teeth 7^c, the said teeth preferably being arranged to face the corresponding doors, and the rear ends of said arms being formed with integral hooks 7^d, for facilitating attachment of a common spring 8, whose tension is exerted for normally spreading and holding the free ends of said arms in the latching position, as shown by the full lines in Fig. 1. The construction and arrangement of the arm 7—7' is such that, the teeth 7^c are normally disposed across the paths of the adjacent flanges 4^d, so that when the doors 4—4' are raised, as shown by dotted lines in Fig. 2, the flanges 4^d engage the inclined edges 7^e of the latches, and force the arms outwardly until the flanges 4^d reach and snap behind the teeth 7^c, as shown in Fig. 2. The tension of the spring 8 effects this automatic latching of the doors 4—4', and holds the said doors open. The swinging of the arms 7—7' against the tension of spring 8, as to

the dotted position, shown in Fig. 1, frees the teeth 7^c and permits the doors to be closed.

Figs. 3 and 4 illustrate a modified fastener, consisting of a perforated base 9, which may be rigidly secured to the outer cylinder 2', by means of screws 9'. Upon this base 9 is mounted transversely a plate 9^a, which is held in place by a screw 9^b, the latter being threaded into the base, and the said plate being rendered adjustable lengthwise, by means of a slot 9^c, through which the screw 9^b passes. The free end of the plate 9^a is perforated and supports one end 15 of a latch-bar 10, the latter being perforated to receive a screw 10', by which the bar is pivotally held in place. The bar 10 is also provided with a shoulder 10^a, which engages the rear edge of plate 9^a, for limiting the swinging movements of the said bar, as shown by the full and dotted lines in Fig. 3. A spring 12 anchored to the base 9, and engaging a hook 10^b of the latch-bar 10, tends to resiliently hold the said bar in the 20 full line or latching position, shown in Fig. 3. Between the pivot 10', and its free end the bar 10 is formed with a tooth 10^c which over-laps the flange 13, of a single door 13' carried by a cylindrical washing member 30 13^a, the same as the latch-bars 7—7'. The raising of the door 13' swings the bar 10 toward the dotted position, shown in Fig. 3 sufficiently to allow the flange 13 to snap behind the tooth 10^c for holding the door open, 35 as explained.

The fastener herein described and shown is extremely simple, and when properly constructed, applied and adjusted, positively holds the doors at the proper angle relatively 40 to the door openings, and when so installed the fastener needs no attention except to release the latch-bars for closing the doors. The fasteners obviate the danger of the doors being accidentally released and falling, and when mounted as shown in the 45 drawings, neither pedestals or latch-bars interfere with the operation of the washers. The present fastener contains but a few parts, and may be produced and installed at 50 small expense.

Having thus described my invention what I claim is—

1. The combination with a laundry washer having spaced doors, of a fastener comprising a pedestal mounted upon the washer between said doors, a plate mounted rigidly upon said pedestal, latch bars pivotally supported by said plate, said bars being disposed parallel to the ends of the doors, the 55 said bars being formed with teeth that face the doors, and said teeth overlapping the end 60

65 margins of the doors, and tension means for spreading the free ends of said bars for resiliently holding the teeth in the latching position.

2. The combination with a laundry washer having spaced doors, of a fastener comprising a pedestal mounted upon the washer between said doors, latch-bars pivotally supported by said pedestal, said bars being disposed parallel to the ends of the doors and overlapping said ends, said bars having teeth that overhang the margin of said ends, said bars adapted when frictionally engaged by said margin to swing away from the 70 doors, and tension means for moving the bars toward the doors and causing said teeth to grip said margin for holding the doors open.

3. The combination with a cylindrical 75 laundry washer having openings and an inner cylinder having coinciding openings closed by swinging doors, of a fastener comprising a pedestal mounted upon the outer cylinder between said aligning openings, a 80 perforated plate mounted upon said pedestal, similar latch-bars pivotally mounted upon said plate by means that engage said perforation, said latch-bars having shoulders for loosely engaging an edge of said 85 plate for limiting the swinging movements of said latch-bars, said latch-bars extending forwardly and overhanging the adjacent margins of said doors and having teeth facing the doors adapted to grip said margins 90 for holding the doors in open position, and a spring interposed between the shoulders of said latch-bars for resiliently holding the 95 free ends of said bars spread apart.

4. The combination with a laundry washer 100 having openings closed by upwardly swinging doors, of a fastener comprising a pedestal mounted upon the washer between said doors, a plate supported by said pedestal a 105 pair of latch-bars having their corresponding ends pivoted to said plate the opposite ends of said bars being extended and overlapping the corresponding margins of said doors, means for limiting the spreading of the free ends of said bars, tension means for 110 normally holding the free ends of said bars spread to the full extent of said limiting means, the remote edges of said bars being formed with teeth that overhang the margins of the doors, said bars adapted to be moved towards each other by the opening of doors and to spring back toward the doors when the said margins snap into the bights of said teeth.

In testimony whereof I affix my signature.

WILLIAM P. KING.
